DRUM MAKING MACHINE

Louis Pardini, Burlingame, Calif.

Application November 29, 1937, Serial No. 177,010

6 Claims. (Cl. 147—47)

The present invention relates to machines for making containers, in the form of drums or similar articles, from flexible materials such as sheets and strips of wood veneer or compressed fiber.

Containers of this type comprise a body made from a sheet of thin material, with one or more circumferential interior ribs to form shoulders against which the ends or heads are seated, and a number of exterior hoops which reinforce the body. The machine herein illustrated and described, embodying the present invention, assembles the above mentioned parts upon a mandrel, and fastens them together to form the complete container. One end or head, forming the bottom of the container, is assembled with and fastened to the body simultaneously with the assembling and fastening of the hoops. The other end is left open, but is provided with an interior flange upon which a suitable top may be placed after the container is filled.

The principal objects of the invention are to provide an improved form of mandrel and an improved feed table, by means of which the parts are assembled mechanically with speed and accuracy, and which permit the bottom head to be assembled with the body and fastened directly thereto without requiring an interior flange to support it and locate it in proper position; to provide means to enable the completed container to be removed quickly from the mandrel; and to provide means for rotating the mandrel, both in timed relation to the operation of the fastening mechanism, and independently thereof, so that the operator can continue the assembling and fastening operation for more than one complete revolution of the mandrel to accommodate a varying amount of over-lap in the body and hoops, and yet can move the mandrel to its correct position for beginning the next cycle. Other objects and advantages of the invention will be brought to light as the description of the machine progresses.

The particular machine herein shown and described is designed to make cylindrical drums from thin sheets and strips of wood, and to fasten them together by means of wire staples. It will be apparent, however, to those skilled in the art, that the machine may be adapted, without material change, to make tapering baskets, or to use other materials or other fastening means. It is to be understood, moreover, that the several parts herein shown and described may be changed in form, construction and arrangement, within the limits of the claims hereto appended, without departing from the spirit of the invention.

Reference will be made to the accompanying drawings, wherein

Fig. 1 is a front elevation of the complete machine.

Figs. 2, 3 and 4 are detailed side elevations of the control pedals, taken on the respective lines 2—2, 3—3 and 4—4 of Fig. 1.

Fig. 5 is a broken plan view of the feed table.

Fig. 6 is a vertical section taken through the work holding mandrel showing a drum in position 10 thereon.

Fig. 7 is a side elevation of the rear end portion of the mandrel showing one of the expandable chucks thereof.

Fig. 8 is a transverse section of the mandrel 15 taken on the line 8—8 of Fig. 6.

Fig. 9 is a rear elevation of the machine showing the drive mechanism.

Fig. 10 is a side elevation of a portion of the drive mechanism, as viewed from the right of 20 Fig. 9.

Fig. 11 is a detail plan view of the mechanism for locking the drum holder.

Fig. 12 is a side elevation of the upper portion of the machine as seen from the right of Fig. 1, 25 showing a completed drum on the mandrel, the feed table being omitted.

Fig. 13 is a detailed horizontal section taken on the line 13—13 of Fig. 12.

Fig. 14 is a broken sectional detail of the mandrel drive mechanism, taken on the line 14—14 of Fig. 12.

In the drawings, the reference numeral 15 indicates a frame upon which is mounted a motor 16, as shown in Fig. 9. A pulley 17 on the shaft of 35 said motor drives a belt 18 which passes around and drives a pulley 19, positioned near the top of the frame, which drives a shaft 20 through gearing indicated at 20a. The shaft 20 is connected with a shaft 21, Fig. 12, by a clutch 22, 40 said shaft 21 extending across the machine and being provided with a plurality of eccentrics 23. These eccentrics operate a series of identical stapling heads, indicated at 24 in Figs. 1 and 12. The construction of said stapling heads forms 45 no part of the present invention, and has therefore been omitted from the drawings. It will be sufficient to understand that the stapling heads 24 are reciprocated in unison by the eccentrics 23, and that, as a result of such reciprocation, wire 50 staples are driven into the work positioned upon a mandrel or holder 25. One of the wires from which the staples are formed is shown at 26 in Fig. 1. The mechanism and operation of forming staples from the wire and driving them into 55

the work is a matter of common knowledge in the art and need not be described herein.

The materials from which the completed drum is assembled comprise a circular disk of wood 27, Fig. 6, which forms the bottom head of the drum; a relatively narrow, flexible strip of wood 28 which forms a ring inside the drum near its open upper end, upon which the top, not shown, may rest; a sheet of flexible wood veneer 29, which 10 forms the cylindrical body of the drum; and a plurality of flexible strips 30, wider than the strip 28, which form reinforcing hoops on the outside of the body 29. The machine herein illustrated is designed to apply three of such exterior strips to the drum and therefore three stapling heads 24 are indicated in Fig. 12. One of said heads drives a series of successive staples through the upper hoop 30, the body 29 of the drum, and the inner flange 28 (Fig. 6); another 20 head drives a series of staples through the center hoop and the body of the drum; and the third head drives a series of staples through the lower hoop and the body of the drum, and into the edge of the bottom 27. Thus by a successive series of 25 three simultaneous stapling operations, the entire drum is fastened together. At each revolution of the shaft 21, all three stapling heads 24 descend upon the work, each head driving one staple. The mandrel 25 then advances the work 30 one step, and three more staples are driven. This continues until the work has made a full revolution, when the drum is complete.

A feed table 31, Figs. 1 and 5, is positioned at the right hand side of the machine and has an 35 upstanding flange 32 along its rear edge. It also has a groove 33 spaced about one inch from said rear edge. Above the feed table are three pairs of guide rollers 34, each pair of rollers being mounted upon a plate or bracket 35, and all of 40 said brackets being carried by a rod 36 mounted in fixed brackets 36a. At its free end each roller has a flange 37 held against its end by a spring 38. The rod 36 may oscillate in its brackets 36a, permitting the roller brackets 35 to rock.

45 The narrow strip 28 which forms the interior flange within the upper end of the drum is inserted in the groove 33 in the feed table 31. The strips 30 which form the exterior hoops of the drums are inserted between the rollers 34, as 50 shown in Fig. 1, each strip passing over the outer roller and under the inner roller. The sheet of veneer 29 which forms the body of the drum is laid flat upon the feed table with one edge against the flange 32.

55 The work holder or mandrel 25, which is positioned adjacent the inner end of the feed table 31, is mounted upon a rotatable shaft 39, as shown in Fig. 6, and comprises a pair of expandable chucks 40 positioned to grip the interior of 60 the drum inside the upper and center hoops respectively, and to serve as anvils for clinching the staples driven through said hoops. Each chuck comprises four segmental jaws 41, Figs. 6, 7, and 8, carried by tongues 42 which slide in sockets 43 formed in the hub 44. The jaws 41 are connected by toggle links 45 with a yoke 46 slidably mounted upon the shaft 39. A pair of rods 47 are connected with the yokes 46 of both chucks and extend endwise to a sliding collar 48 provided 70 with an annular groove 49. A yoke 50, whose arms are provided with trunnion blocks 51 riding in the groove 49, is operated either by a hand lever 52 or by a pedal 53, Figs. 1 and 4, through a series of connecting links and levers 54. By operating either the hand lever 52 or the pedal 53

the chucks 40 can be expanded or contracted. They are shown in the drawings in contracted position.

The chuck at the rear end of the mandrel is provided with flanged clips 54a, Figs. 7 and 8, 5 between the ends of the segmental jaws 41, one of which receives the leading end of the inside strip 28 as it is fed in from the feed table. The corners of the jaws 41 of said rear chuck are cut away diagonally and roughened or serrated, as 10 shown at 54b, and when said jaws are expanded, the end of the strip 28 is clamped between the clip 54a and the diagonal end of the jaw. The clips 54a are rigidly secured to and extend laterally from a disk or spider 54c formed integrally 15 with the hub 44 of the chuck.

A disk 55, Fig. 6, is secured upon the forward end of the shaft 39. The bottom head 27 of the drum, which is clamped against said disk, is caused to rotate therewith by a plurality of 20 prongs 56 which project from its outer surface and enter the adjacent surface of the wood. The disk 55 is also provided with a central boss 56a, which engages a hole or recess in the head 27, whereby the latter is centered. A clamping plate 25 57, forming an end gate for the mandrel, bears against the outer surface of the head 27 to hold it against the chuck disk 55. The gate 57 is rotatably carried upon a spindle 58, Fig. 13, which is 30 slidably mounted in a bracket 59. The bracket 59 is secured upon the lower end of a rod 60, Figs. 1 and 12, which is mounted for oscillation in a suitable portion of the frame. A spring 61 rotates the rod 60 in a direction to swing the bracket 59 and the gate 57 away from the end of the mandrel 25. The bracket 59 may be swung manually 35 toward said holder, to clamp the head 27 between the gate 57 and the disk 55, and is held in such position, against the tension of the spring 61, by a latch mechanism at the upper end of the rod 40 60. This latch mechanism comprises a cam 62 provided with an abrupt shoulder 63, Fig. 11, which can be engaged by a pawl 64, the latter being moved into and out of engaging position by a hand lever 65. The cam 62 is also provided 45 with a second shoulder 66 which abuts against a fixed lug 67 to provide a positive stop for the outward movement of the bracket 59. The gate 57 is pressed inwardly, toward the disk 55, by a spring 68, Figs. 12 and 13. It may be withdrawn, 50 to free the head 27 without swinging the entire bracket 59 outwardly, by a lever 69 rotatably mounted on the outer end of the spindle 58 and provided with a cam 70 which engages a follower 71 projecting from said spindle. 55

The work is pressed down upon the mandrel by a roller 72, Figs. 1 and 12, which extends the full length of said mandrel and is carried by swinging brackets 73. Said brackets are mounted upon a shaft 74 which is oscillated by a hand lever 75. Springs 76 provide a resilient mounting for the roller 72 in said brackets. A latch 77, connected with the lever 75 and engaging a fixed pin 78, holds the roller 72 down upon the work, clamping said work against the chucks of the 65 mandrel. A spring 78a, Fig. 12, lifts said roller when the latch 77 is disengaged.

The mandrel is rotated, to carry the work beneath the stapling heads 24, by a pawl and ratchet mechanism operated by the eccentric 70 shaft 21 shown in Figs. 12 and 14. An eccentric 79 on said shaft reciprocates a rod 80 whose end is bent to form a pawl 81. Said pawl engages a ratchet wheel 82 upon the mandrel shaft 39. Each upward stroke of the rod 80 rotates the 75

ratchet wheel 82 and the mandrel shaft 39 the distance of one ratchet tooth in a counter-clockwise direction, and upon each downward stroke of said rod 80, the pawl 81 slides outwardly upon the inclined rear face of the ratchet tooth and rides over said tooth, dropping into the next notch. The ratchet wheel, the shaft 39, and the mandrel 25 are prevented from rotating in a reverse or clockwise direction during the downward or return stroke of the pawl 81 by a friction brake to be described hereinafter. Thus upon each upward stroke of the stapling heads the mandrel is rotated one step, to present a new portion of the work beneath said stapling heads.

15 An auxiliary drive mechanism is provided for rotating the mandrel 25 without operating the stapling mechanism. This auxiliary drive comprises a shaft 83, Figs. 9 and 10, driven from the continuously rotating shaft 20 by a chain 84 and gearing 84a. The shaft 83 is connected, through a clutch 85, a short shaft 85a, and a chain 86, with the mandrel shaft 39. The clutch 85 is operated by linkage 87 and a rock-shaft 88, the latter being connected with a pedal 89 by linkage 90, as shown in Fig. 3. Depressing the pedal 89 engages the clutch 85, causing the mandrel 25 to be rotated by the chains 84 and 86 and the shaft 83, without operating the stapling mechanism. A spring 91 disengages said clutch 30 85.

A positive stop latch is provided for limiting the forward movement of the mandrel at the end of each cycle of operation, comprising an arm 92, Figs. 1 and 10, positioned to engage the ratchet wheel 82. Said arm, which is fulcrumed at 93, is lifted out of locking position by the linkage 94 connected with the rock shaft 88 operated by the pedal 89. The arm 92 is also lifted out of locking position, automatically, by a cam 95 on the shaft 40 85a of the clutch 85. The spider 54c of the rear mandrel chuck has a peripheral face 96, Figs. 1 and 6, against which a friction brake 97 operates, said brake being resiliently held against said face by a spring 97a whose tension is adjustable by a 45 screw 97b. The brake 97 prevents reverse movement of the mandrel by the ratchet pawl 81.

The clutch 22 is controlled by a pedal 98, Figs. 1, 2 and 12, through linkage 99. Depressing said pedal engages the clutch, and a spring 100 releases it. Depressing said pedal also raises the stop latch 92 out of locking engagement with the ratchet wheel 82, through an interconnecting link 99a, Fig. 10, between the clutch rod 99 and the latch rod 94. When the clutch is released, 55 the latch drops into engagement with the ratchet wheel to stop the mandrel.

In using the machine, the operator first places the bottom head 27 against the mandrel disk 55, clamping it in position with the gate 57. He then turns the mandrel, without operating the stapling mechanism, by means of the auxiliary drive controlled by the pedal 89, until one of the clamping clips 54a of the rear chuck is at the top and in line with the feed table. The inside strip 28 is then laid in the groove 33 of said feed table, and pushed inwardly until its end is engaged beneath said clip 54a. The jaws of said rear chuck have a peripheral groove 33a, Fig. 6, in line with the groove 33 of the table, to receive the strip 28.

The mandrel is then expanded, by means of the lever 52 or the pedal 53, to clamp the end of the strip 28 beneath the clip 54a, and said mandrel is again rotated by means of the pedal 89, without operating the stapling mechanism, thereby 75 pulling the strip 28 around with it until the lead-

ing end of said strip has passed beneath the line of the stapling heads. The body sheet 29 is then laid upon the feed table and pushed in until its leading edge is beneath the stapling heads 24. The rear chuck has a peripheral flange 32a 5 aligned with the flange 32 of the table, these flanges guiding the body sheet 29 to proper position. The outside hoop strips 30 are threaded through their respective pairs of guide rollers 34, and are pushed in until their ends are also beneath the stapling heads 24. Lugs 101, Fig. 1, project from the bottoms of said stapling heads, and act as stops to locate the proper initial positions of the body sheet 29 and the hoop strips 30.

Having placed the various component parts of 15 the drum in their proper positions, the operator brings down the clamping roller 72, by means of its lever 75, thereby clamping said parts against the mandrel. He then starts the stapling operation by depressing the pedal 98. The first stitch 20 or staple unites the outside hoop strips 30 with the body sheet 29, and also unites said body sheet with the inside strip 28, whose end is clamped between the mandrel chuck and the clip 54a. Therefore, as the mandrel rotates with its step by 25 step motion between successive staplings, all the various parts of the drum are pulled around with it and wound upon it. When the mandrel has made one complete revolution and enough more to fasten down the necessary overlap of the body 30 and hoops of the drum, the operator releases the pedal 98 and the machine stops. He then releases the clamping roller 72 by unlatching the lever 75 and at the same time releases the latch lever 65 to allow the gate 57 to swing outwardly 35 away from the end of the mandrel. Finally, he contracts the chucks, either by the lever 52 or the pedal 53, and removes the finished drum from the mandrel.

It will be recognized by those skilled in the art 40 that the provision of means for turning the mandrel without operating the stapling mechanism makes for greater flexibility and convenience in operating the machine. The body sheet and the outside hoops of the drum must have some overlap, and therefore the stapling operation must continue for slightly more than one revolution of the mandrel. In my machine, the operator can continue the stapling as much beyond one revolution as may be necessary to fasten the overlapping ends of the body and hoops, and if these parts are somewhat longer than standard, as they frequently are, no trouble is caused thereby.

This flexibility in the duration of the stapling operation, however, causes the mandrel to stop in 55 random positions. The proper termination of the stapling operation may leave the mandrel in such a position that the end of the strip 28 for the next drum cannot be inserted beneath one of the clips 54a. In this event, the operator, as 60 he places the strip 28 on the feed table, rotates the mandrel, without operating the stapling mechanism, by pressing the pedal 89, until one of the clips 54a comes to proper position.

The means for rotating the mandrel without 65 operating the stapling mechanism also permits the operator, if he so desires, to make the body sheet lead the hoops by a sufficient distance so that they do not overlap at the same place, thereby making a neater and better drum than would 70 be the case if the trailing end of the body sheet overlapped the leading ends of the hoops. In order to accomplish this result, the corner of the body sheet 29 is inserted beneath the clip 54a of the mandrel on top of the inside strip 28, as 75

shown in Fig. 8, and both are clamped together to the mandrel. Initial rotation of the mandrel, without operating the stapling mechanism, thereupon pulls both the strip 28 and sheet 29 under the stapling heads and as much beyond the ends of the hoop strips 30 as may be required to stagger the overlaps. This lead of the body sheet ahead of the hoop strips is maintained throughout the stapling operation, and enables the overlap 10 of the body to be completed before that of the hoops begins.

It will also be seen that the construction of the mandrel and the feed table are such as to insure the correct assembling of all parts of the 15 drum. The bottom head 21, being clamped to the end of the mandrel, forms a part thereof, the lower end of the body sheet being wound directly and tightly about said head. By making said head of sufficiently thick wood, and driving the 20 bottom row of staples directly into its edge, there is no necessity for interior hoops at this end of the drum.

I claim:

1. In a machine for making drums from sheets 25 and strips of flexible material, a rotatable mandrel upon which said material is wound in simultaneously applied superposed layers, clamping means on said mandrel within the outer periphery thereof for gripping the leading end of an inner 30 layer of material and causing it to advance with the initial rotation of said mandrel, stop means positioned outside the outer periphery of said mandrel for temporary engagement with an outer layer of material to prevent it from advancing 35 with said inner layer during said initial rotation of the mandrel, and means for uniting said layers together during the subsequent rotation of said mandrel.

2. In a machine for making drums from sheets 40 and strips of flexible material, a mandrel upon which said material is wound in superposed layers, fastening means for securing said layers of material together while upon said mandrel, means for rotating said mandrel and operating 45 said fastening means in timed relation, other means for rotating said mandrel alone, a clamp on said mandrel within the outer periphery thereof for gripping the leading end of an inner layer of material, and stop means exterior to said 50 mandrel positioned for temporary engagement with an outer layer of the material, said clamp and said stop means permitting said inner layer to be advanced relative to said outer layer when the mandrel is rotated without operating the 55 fastening means.

3. A machine for making drums from flexible sheets and strips comprising a rotatable mandrel about which the sheet and strips are wound into cylindrical shape, intermittently operating fastening means for securing said sheet and strips together, intermittent drive mechanism engageable with said mandrel to impart step-by-step rotation thereto, said drive mechanism operating in timed relation to the operation of said fastening means, continuously moving drive mechanism engageable with said mandrel to impart continuous rotary movement thereto, a latch member movable into and out of engagement with said mandrel to stop the rotary movement thereof, 70 control means acting upon said drive mechanisms to connect either of them with said mandrel, and interconnecting means between said drive mechanisms and said latch member operable to move said latch member out of engagement with said

mandrel when either of said drive mechanisms is connected therewith.

4. A machine for making drums from flexible sheets and strips comprising a rotatable mandrel about which the sheet and strips are wound into cylindrical shape, intermittently operating fastening means for securing said sheet and strips together, a ratchet wheel connected with said mandrel, intermittent drive mechanism for imparting step-by-step rotation to said mandrel, 10 said drive mechanism operating in timed relation to the operation of said fastening means and including a reciprocating pawl engageable with said ratchet wheel, continuously moving drive mechanism engageable with said mandrel to impart 15 continuous rotary movement thereto, a latch member movable into and out of engagement with said ratchet wheel to stop the rotary movement of said mandrel, control means operable at will and acting upon said drive mechanisms to 20 connect either of them with said mandrel, and interconnecting means between said drive mechanisms and said latch member operable to move said latch member out of engagement with said ratchet wheel when either of said drive mechanisms is connected in driving relation with said 25 mandrel.

5. In a machine for making drums from sheets and strips of flexible material, a mandrel comprising an expandable chuck, said chuck having a 30 plurality of radially movable segmental jaws, the outer faces of said jaws complementing each other to form a cylindrical mandrel surface about which the drum-forming material is wound, one of said jaws having a portion of its outer face at one of its ends depressed below the periphery of said mandrel surface, a lug rigidly secured to said mandrel, said lug having an approximately radially disposed portion lying between the depressed end of the last mentioned jaw and the end of the 35 adjacent jaw, and said lug having a tangentially disposed portion overlying said depressed jaw portion and forming therewith a clamp to receive and grip the leading edge of the drum-forming material, the outer surface of said tangential lug portion being flush with the outer cylindrical faces of said jaws when the latter are in expanded position.

6. In a machine for making drums from sheets and strips of flexible material, a mandrel comprising an expandable chuck, said chuck having a 40 plurality of radially movable segmental jaws, the outer faces of said jaws complementing each other to form a cylindrical mandrel surface about which the drum-forming material is wound, 45 one of said jaws having a portion of its outer face at one of its ends depressed below the periphery of said mandrel surface, a disk secured at one end of said mandrel adjacent to said chuck, said disk being larger in diameter than the chuck 50 when in expanded position, a lug secured to and projecting laterally from said disk, said lug having an approximately radially disposed portion lying between the depressed end of the last mentioned jaw and the end of the adjacent jaw, and said lug having a tangentially disposed portion 55 overlying said depressed jaw portion and forming therewith a clamp to receive and grip the leading edge of the drum-forming material, the outer surface of said tangential lug portion being flush with the outer cylindrical faces of said jaws when the latter are in expanded position.
